UNITED STATES PATENT OFFICE.

JOSEPH K. DAVIS, OF WATERBURY, CONNECTICUT, ASSIGNEE TO SCOVILL MANUFACTURING COMPANY, OF WATERBURY, CONNECTICUT, A CORPORATION OF CONNECTICUT.

DRAFT-DEFLECTOR FOR LAMP-BURNERS.

1,151,512.

Specification of Letters Patent. Patented Aug. 24, 1915.

Application filed June 14, 1915. Serial No. 33,977.

To all whom it may concern:

Be it known that I, JOSEPH K. DAVIS, a citizen of the United States, residing at Waterbury, in the county of New Haven 5 and State of Connecticut, have invented a certain new and useful Improvement in Draft-Deflectors for Lamp-Burners, of which the following is a full, clear, and exact description.

10 This invention relates to the type of draft deflectors for lamp burners forming the subjects of the Coons Patent No. 1,087,280 and the Sanderson Patent No. 1,087,323, both dated February 17, 1914, and the object of 15 the invention is to adapt deflectors of this type for use in the smaller sizes of burners, and at the same time conserve the advantages of the deflectors of the Coons and Sanderson patents in the control of the draft 20 and the consequent production of good illumination.

In this invention, as in the inventions of the patents mentioned, the deflector is preferably formed of a single piece of sheet 25 metal, without seams, and the deflector is provided with corner projections at its top which engage a horizontal groove surrounding the flame slot in the burner cone in order to support the deflector in position so as to 30 insure a passage all around it both between itself and the wick tube and itself and the surrounding cone, thus affording practically unimpeded and unobstructed passageways for the draft; there being provided preferably, means to prevent the deflector from 35 turning in the cone, as I will proceed now to explain and finally claim.

In the accompanying drawings illustrating 40 the invention, in the several figures of which like parts are similarly designated, Figure 1 is a perspective view of the deflector and Fig. 2 is a side elevation thereof. Fig. 3 is a top plan view of a burner with the deflector in position, the cone being in 45 horizontal section on the plane of line A B, Fig. 4. Fig. 4 is a transverse section of the cone and deflector, the section being taken in the plane of line C D, Fig. 3, and the spring catch of the cone broken off. Figs. 5, 50 6, 7 and 8 illustrate the blank, and first, second and third operations employed in forming the deflector, the finished article of the final step being similarly shown in Fig. 3.

All of the views are enlarged, but they are intended to show the invention in its special 55 use on the smaller sizes of lamp burners.

The deflector comprises the side walls 1, the end walls 2 provided with the vertical corrugations or grooves 3, and the open top surrounded by the connecting top web 4, 60 all in one piece, without seams or joints. The side walls and the end walls may be respectively parallel or divergent or inclined, as may be desired. These walls are separated at the corners by open spaces 5, 65 and the top web 4 has the outwardly extending projections 6 overlying these spaces and serving to engage the knurl or groove 7 in the burner cone 8 surrounding the flame slot 9 therein horizontally, in order to support 70 or suspend the deflector in the cone free of the cone, wick tube 10, and perforated distributor plate 11 of the burner 12. These projections are of arch form transversely 75 for strength and so as to afford the least possible obstruction to the flow of air. The deflector is snapped or sprung into the groove, without the necessity of cutting holes in the cone, and it is held in position therein and kept from turning by means of the indentations 13 in the groove which coöperate with the adjacent projections for the purposes stated. Instead of indentations any other suitable obstructions may be used to keep 80 the deflector in alinement with the flame slot 85 in the cone, or with the wick-tube. Preferably, these indentations are so located as to come between two adjacent projections, to thus resist turning in opposite directions.

Preferably the top web of the deflector is 90 inclined slightly at its sides and pronouncedly at its ends, as indicated at 14 and 15, respectively, for strength and to facilitate and direct the passage of the air both 95 through the interior of the deflector and outside of it.

In the manufacture of the deflector, a blank such as shown in Fig. 5, may be used, and this blank is then bent so as to turn down the sides and ends and initially form 100 the corner projections, as shown in Fig. 6. Next the top is depressed as its ends and the projections further developed, as in Fig. 7, and then the center of the blank is cut out and the contour further developed, as in Fig. 105 8, and finally the end corrugations or

grooves supplied, as in Figs. 1, 2, 3 and 4. The inclination of the top web at the ends directs the draft toward the center of the flame, or, rather, away from its ends, and 5 serves to keep the flame in shape to give the best illuminating effect. The inclination of the side walls is less pronounced but sufficient to direct the air properly with relation to the flame. The end corrugations or 10 grooves subserve the same purpose as the similar parts or air ducts in the patents first referred to, and further make the principle of those deflectors efficiently applicable to the smaller sizes of lamp burners. The invention, however, is not restricted in use to any 15 particular size of burner.

The corrugations or grooves may or may not be used, or they may be replaced by other equivalent means; and other variations 20 are intended to be within the scope of the claims following.

What I claim is:—

1. A draft deflector for lamp burners, 25 having side walls, end walls, a top web, and corner projections extending out laterally from the top web and adapted to engage a groove in the burner cone to support the deflector therein.

2. A draft deflector for lamp burners, 30 having side walls, end walls, a top web, and corner projections of arch form in cross-section and end view and extending out laterally from the top web and adapted to engage a groove in the burner cone to support the deflector therein.

3. A draft deflector for lamp burners, 35 having side walls and end walls with intervening open spaces at the corners, a top web, and corner projections overlying said open spaces and extending out laterally from the top web and adapted to engage a groove in

the burner cone to support the deflector therein.

4. A draft deflector for lamp burners, 45 having side walls, end walls, a top web inclined next to the ends, and corner projections extending out laterally from the top web and adapted to engage a groove in the burner cone to support the deflector therein.

5. A draft deflector for lamp burners, 50 having side walls and end walls separated by intervening spaces at the corners of the deflector, the end walls having vertically disposed corrugations, a top web, and arched projections extending laterally from the top 55 web over the open corners and adapted to engage a groove in the burner cone to support the deflector therein.

6. A draft deflector for lamp burners, 60 having side walls, end walls, a top web, and corner projections extending out laterally from the top web and adapted to engage a groove in the burner cone to support the deflector therein, combined with means to position the deflector in the cone and prevent 65 it from turning.

7. A draft deflector for lamp burners, 70 having side walls, end walls, a top web, and corner projections extending out laterally from the top web and adapted to engage a groove in the burner cone to support the deflector therein, combined with an obstruction in the groove to engage the projections to prevent the deflector from turning in the 75 cone.

In testimony whereof I have hereunto set my hand this 11th day of June A. D. 1915.

JOSEPH K. DAVIS.
